SOLDERING TOOL HOLDER

Alvis R. Knowles, Manhattan Beach, Calif., assignor to
Ungar Electric Tools, Inc., Los Angeles, Calif., a cor-
poration of California

Application August 18, 1958, Serial No. 52,246

Term of patent 14 years

(Cl. D26—1)

Figure 1 is a perspective view of a soldering tool holder, showing my new design;

Figure 2 is a side elevational view, to an enlarged scale; and

Figure 3 is a rear elevational view thereof, to an enlarged scale.

The broken line showing of a soldering tool and connecting wire is for illustrative purposes only.

I claim:

The ornamental design for a soldering tool holder, as shown and described.
